UNITED STATES PATENT OFFICE.

WILLIAM HUBBARD, OF ROCHESTER, NEW YORK, ASSIGNOR TO UNITED SHOE MACHINERY CORPORATION, OF PATERSON, NEW JERSEY, A CORPORATION OF NEW JERSEY.

METHOD OF MAKING SHOES.

1,401,258.

Specification of Letters Patent. Patented Dec. 27, 1921.

Application filed January 28, 1920. Serial No. 354,716.

To all whom it may concern:

Be it known that I, WILLIAM HUBBARD, a citizen of the United States, residing at Rochester, in the county of Monroe and State of New York, have invented certain Improvements in Methods of Making Shoes, of which the following description in connection with the accompanying drawings is a specification, like reference characters 10 on the drawings indicating like parts in the several figures.

This invention relates to shoemaking and more especially to methods of making covered heels.

15 In the manufacture of heels composed of a plurality of lifts it is customary to make the heel-blanks or bodies by various heel-building operations and thereafter to attach the heel-blanks to the shoes by machinery 20 that determines the desired relation of the heel-blank to the shoe and that secures to the attached heel-blank a toplift that has previously been formed approximately to the desired final contour. One reason for 25 imparting approximately the desired contour to the toplift before attaching the latter to the untrimmed heel arises from the fact that the toplift is utilized as a templet by which to trim or shave the body of the 30 heel after it has been attached to the shoe, and for such practice heel-trimming machines are provided with work-guiding devices called toplift-guards that bear against the edge of the toplift and thereby guide 35 the body of the heel relatively to a rotary cutter so as to enable the operative to trim the body of the heel according to the outline of the toplift. The practice above described has been followed generally in 40 the manufacture of heels that are not to be provided with covers, and also to some extent in the manufacture of those that are to be provided with covers. In the latter case the procedure has been substantially as follows: First, to attach a previously formed 45 toplift to the untrimmed heel-body; second, to trim the heel-body and the toplift to final shape; third, to scour the heel-body and the toplift; fourth, to detach the toplift

from the heel-body; fifth, to apply the cover 50 to the heel-body so that the lower marginal portion of the cover will be folded inwardly and cemented to the bottom of the heel-body; sixth, to attach a new toplift slightly larger than the trimmed heel-body; and 55 seventh, to trim the new toplift while the latter is attached to the covered heel.

The reason for attaching a new toplift instead of the one that was originally attached and trimmed with the heel-body is 60 that, since the edge of the original toplift as trimmed with the heel-body is flush with the body of the heel before the cover is attached, and since the cover increases the lateral dimensions of the heel-body beyond those of the original toplift, the latter is too small and therefore would spoil the lines and the appearance of the heel if it were reattached. Consequently, in order 65 to obtain the desired lines and appearance 70 it has been necessary to sacrifice the original toplift, and this has entailed considerable waste, the saving of which is an object of this invention.

Broadly stated, the present invention provides an improved method of making covered heels by which the desired lines and appearance of the completed heel may be obtained without wasting lifts and without sacrificing any of the advantages of utilizing a toplift of approximately final contour as a templet when trimming the body of the heel preparatory to applying the heel-cover.

According to my present improved method 85 a templet is attached to the untrimmed heel-body to guide the latter relatively to the cutter by which it is to be shaped. This templet may be, in fact, the toplift that will form a part of the completed heel, although it would be within the scope of the invention to use for this purpose a templet that could be used repeatedly with an indefinite number of heels to promote successive trimming operations. In any event, 90 whether the templet is or is not the toplift that is to form a part of the finished heel, it preferably embodies substantially the de-

sired final contour of the toplift although it may be slightly larger than final size without defeating the purposes or advantages of the invention. The next step in my present 5 method is to trim the heel-body by the guidance of the templet, at the same time leaving the templet larger in its lateral dimensions than the contiguous portion of the heel-body. Then, in the event that the tem- 10 plet is the toplift that is to form a part of the finished heel, it will be enough larger than the contiguous portion of the covered heel to provide sufficient stock to insure the desired lines and appearance when the heel 15 is completed. After trimming the body of the heel the templet is detached, and then if it is desired to scour the heel the scouring operation is performed while the toplift is detached. After this, the cover of leather, 20 cloth, or other thin sheet material, will be applied to the heel-body and its lower marginal portion will be folded inwardly and cemented or otherwise secured to the bottom of the heel-body. Then the original 25 toplift, if one has been previously attached to the heel-body to serve as a templet for trimming, will be re-attached in registration with its original position on the heel-body, or if a templet other than such toplift has 30 been used to promote the trimming operation, a toplift larger than the contiguous portion of the heel-body will be attached by any of the means usually employed for attaching toplifts. Then, if necessary, the 35 toplift will be trimmed according to the contour of the contiguous portion of the covered heel-body, and afterward the beveling, edge-setting, staining, burnishing, or other desired finishing operation or opera- 40 tions will be performed on the toplift, according to its requirements.

For purposes of illustration the accompanying drawings show a heel in successive stages of development according to one 45 practicable aspect of the present invention, and while these drawings disclose the method as it may be practised on a heel composed of a large number of lifts, and upon a heel that has been attached to a shoe, the 50 invention is not to be understood as being limited to a heel of the construction shown, nor to a heel of the style shown, nor to a heel that has been attached to a shoe prior to practising such method, since it would not be 55 necessary or feasible for present purposes to show more than one adaptation of the method in order to disclose the principles of the invention.

Referring to the drawings, 60 Figure 1 represents a vertical cross-section through a built-up heel attached to a shoe and provided with a templet in the place of the toplift, the body of the heel being untrimmed but the proposed shape to be 65 produced by trimming being indicated by

broken lines. This figure includes also a plurality of nails that would ordinarily be required in a heel of the style shown, and although Figs. 4, 5, 6 and 8 represent the same heel in successive stages of development the nails have been omitted from the latter figures merely to simplify the drawings and to avoid confusion. For the same reason much of the usual cross-hatching has been omitted. 75

Fig. 2 represents a shoe such as that shown by Fig. 1 in coöperative relation to a heel-trimming machine, the heel being shown as having partly undergone a trimming operation. 80

Fig. 3 represents a view similar to Fig. 2, showing a later stage in the trimming of the heel-body. 85

Fig. 4 is a view similar to Fig. 1, showing the heel as having been trimmed approximately to the desired shape. 90

Fig. 5 is a view similar to Fig. 4 excepting that the templet is omitted to represent the fact that it has been detached from the trimmed heel. 95

Fig. 6 is a view similar to Fig. 5 excepting that the heel-cover has been applied to the heel-body. 90

Fig. 7 is a side elevation of the heel portion of the shoe representing the heel-body as having the cover applied to it, broken lines being included to represent the location of the toplift when the latter has been finally attached. These dotted lines also represent a possible shape to which the toplift may be 100 trimmed. 95

Fig. 8 is a view similar to Fig. 6 excepting that the unfinished toplift has been attached to the covered heel. 105

Fig. 9 is a vertical cross-section through the shoe looking toward the heel-end from a transverse plane in front of the heel, and represents the latter as having been completed to the extent of trimming the toplift to the final shape, and also represents the 110 heel as having a breast-facing applied thereto. 110

The principal elements included in Fig. 1 are a shoe-upper 10, insole 11, outsole 12, base section 13, top section 14, templet 15, 115 heelseat nails 16, heel-attaching nails 17, and nails 18 connecting the top section 14 with the base section 13. A last 19 is represented as having the usual heelseat plate 20 of sheet metal to turn and clinch the heelseat nails 120 and the heel-attaching nails, as shown. The templet 15, as shown, is a toplift. Since the present prevailing style of heels of the character shown calls for an ornamental lift of soft sheet-metal between the toplift 125 and the covered heel-body, such ornamental lift is included and is indicated at 21.

Heel-bodies of the style shown are usually made in two sections 13 and 14 in order to provide the "pitch" required of the heelseat, 130

and accordingly the base section 13 is shown as being anchored to the shoe by the attaching nails 17 while the top section 14 is shown as being anchored to the base section 5 by the connecting nails 18. Furthermore, in accordance with the usual practice, the lower ends of the nails 18 are represented as projecting beyond the first cover-receiving lift 22 in order to provide means for anchoring 10 the toplift to the section 14 by what is sometimes called "blind nails". Any suitable or preferred heel-attaching machine, or other means, may be used to assemble the elements as shown by Fig. 1, with due regard 15 to the location of the templet 15 so that the latter, having been previously shaped approximately to the desired final contour, will serve as a guide by which to trim the body of the heel.

20 Since the heel shown has extreme height or depth, and consequently has a considerable pitch, Figs. 2 and 3 are made to show two successive trimming operations which are usually desirable if not actually necessary with heels of this style. Referring to Fig. 2, the trimming cutter 23, which may be regarded as being one of a plurality of similar cutters carried by a rotary head, is shaped to impart the desired curvature to 25 the lower portion of the heel-body. In Fig. 2 the templet 15 is shown as bearing against a guiding element or guard that bears a pre-determined relation to the field of operation of the cutter or cutters 23, this guard having 30 a base surface 24 for engaging the flat face of the templet and having a shoulder 25 for engaging the edge of the templet. A counter-guard is indicated at 26 and, in accordance with well-known construction in 35 heel-trimming machines, it would preferably be under the influence of a spring or other means tending to move it in the direction indicated by an arrow, in order to maintain the flat face of the templet 15 against 40 the surface 24 of the templet-guard. It is to be observed that the clearance between the surface 24 and the field of operation of the cutter is as great as the thickness of the templet, and consequently it will be apparent 45 that so long as the templet remains as it should, against the surface 24, it will not be spoiled by the cutter. In order, however, to avoid trimming the metal lift 21 too much it would be preferable to provide the cutters 23 with notches, as shown, even though 50 this results in leaving a thin flange 27 of untrimmed stock on the first cover-receiving lift 22. When such a flange is formed it may be removed by a scouring operation 55 after the templet has been detached from the trimmed heel-body.

After trimming the lower part of the heel-body by the cutters 23 the heel may be presented to a rotary cutter such as that indicated at 28 in Fig. 3 to trim the back and

sides of the heel-base and the heel seat portion 29 of the outsole. The cutter 28, as shown, is provided with a rand-crease guard 30 and with a guard 31 arranged to bear on the previously trimmed portion of the heel. 70 As shown by Fig. 3, the heel is arranged to receive the first cut or "roughing cut" by the cutter 28 and when this has been completed it may be presented to the cutter a second time to effect a final cut so as to make the 75 two trimmed portions flush relatively to each other. This part of the trimming operation determines the contour of the base portion of the heel according to the counter portion of the shoe, and blends the base portion with the portion that was previously trimmed according to the contour of the templet 15.

When the back and sides of the heel-body have been trimmed the heel will be in the 80 condition represented by Fig. 4, and the next step will be to remove the templet 15 and the plate 21 if such plate is present. The remaining heel-body will then appear as represented by Fig. 5, and may then be, if 85 it has not already been, presented to a breast- 90 ing machine to shape the breast according to the shape represented by broken lines in Fig. 2 or according to any other desired shape. The heel is thus developed to a condition where it may be scoured to smooth the trimmed surface, to remove any shoulder that may have been formed by failure to blend the two trimming operations, and to remove the thin flange 27 of the second lift, 95 provided such flange has been formed.

The next step would be to apply a cover 32 to the back and sides of the trimmed heel-body. The upper marginal portion of such cover would be tucked into the rand-crease, 100 as shown by Fig. 6, and the lower marginal portion would be folded inwardly against the bottom face of the second lift. The front marginal portion would usually be folded inwardly against the breast of the heel to be 105 covered finally by a suitable breast-facing. If the cover 32 is made of leather or textile fabric it would preferably be fastened to the heel by cement.

Fig. 7 represents an outsole as having 110 been split to form a breast-facing 33, and the latter is represented as having been cemented to the breast of the heel and as having 115 been trimmed to conform to the edges defined by the breast and sides of the heel. 120 After the heel has been thus covered the original toplift and metal plate 21 or, in fact, any suitable toplift with or without a metal plate may be attached as shown by Fig. 8. If the toplift has been previously 125 attached to serve as a templet for trimming, it will have been penetrated by the nails 18 so that when it is re-attached the nails and the penetrations formed thereby will insure the original registration of the 130

toplift with the heel-body. The anchoring of the toplift may be supplemented by additional means such as tacks or slugs. In some cases a screw is inserted approximately 5 at the center of the toplift.

The covered heel is thus provided with a toplift the lateral dimensions of which will be as great as, and usually greater than, those of the covered heel-body and if such 10 toplift is too large or if its edge does not embody the desired bevel or other formation it may be trimmed to any final shape desired. For example, the re-attached toplift is shown by Figs. 7 and 9 as having been 15 beveled according to the flaring formation of the heel-body and consequently it would, in most cases, be desirable to bevel the lower edge as shown in these figures. Trimming machines for this purpose are capable of 20 trimming not only the leather of the toplift but also soft metal such as aluminum or a soft alloy of which the ornamental plate 21 may be composed.

From the foregoing description it is to be 25 observed that my improved method provides for trimming the base portion of the heel according to the shape of the shoe to which the untrimmed heel-body has been attached, and provides also for trimming the remainder 30 of the heel according to a previously formed templet that has been attached in a predetermined position upon an untrimmed heel, and that no part of the heel is wasted or injured incidentally to practising such method.

Having thus described my invention, what I claim as new and desire to secure by Letters Patent of the United States is:

1. That improvement in methods of making 40 shoes which consists in attaching an untrimmed heel having a toplift of approximately final shape, trimming the heel so as to make the first lift of the heel-body smaller than the toplift, detaching the toplift, applying a cover to the heel, and reattaching the original toplift in registration with its original position on the heel-body.

2. That improvement in methods of making 50 shoes which consists in attaching an untrimmed heel, trimming the heel to the contour of the counter portion of the shoe and to that of the toplift while maintaining the original contour of the toplift, detaching the toplift, applying a cover to the remaining heel-body, and re-attaching the original toplift.

3. That improvement in methods of making 60 shoes which consists in attaching an untrimmed heel, trimming the heel to the contour of the counter portion of the shoe and to that of the toplift while maintaining the original contour of the toplift, detaching the toplift, scouring the remaining heel-body, applying a cover to the scoured heel-body, 65 and re-attaching the original toplift.

4. That improvement in methods of making 70 shoes which consists in attaching an untrimmed heel having a templet in the place of the toplift, trimming the heel according to the templet while maintaining the original contour of the templet, detaching the templet, applying a cover to the heel, and attaching a toplift to the covered heel.

5. That improvement in methods of making 75 shoes which consists in attaching an untrimmed heel having a templet in the place of the toplift, trimming the heel according to the templet while maintaining the original contour of the templet, detaching the templet, applying a cover to the heel, and so attaching to the covered heel a toplift of substantially the shape and size of the templet.

6. That improvement in methods of making 85 shoes which consists in attaching an untrimmed heel having a toplift of substantially final shape and size, trimming the heel according to the toplift so as to make the first lift of the heel-body smaller than the toplift, detaching the toplift, scouring the 90 remaining heel-body, applying a cover to the heel-body, re-attaching the original toplift, and operating upon the latter while held by the covered heel.

7. That improvement in methods of making 95 shoes which consists in attaching an untrimmed heel having a toplift of substantially final shape and a lift of soft metal interposed between the toplift and the first lift of the heel-body, trimming the heel above 100 said metallic lift according to the contour of the toplift so as to make the first lift of the heel-body smaller than the metallic lift, detaching the toplift and said metallic lift, applying a cover to the remaining heel-body, 105 re-attaching the original toplift and metallic lift, and thereafter trimming the metallic lift and the toplift.

8. That improvement in methods of making 110 shoes which consists in attaching an untrimmed heel having a toplift of substantially final outline, trimming the first and other lifts of the heel-body so as to make the first lift smaller than the toplift, detaching the toplift, applying a cover to the remaining heel-body, and re-attaching the original toplift with a metallic lift interposed between it and the first lift of the covered heel-body.

9. That improvement in methods of making 115 covered heels which consists in shaping a heel-body according to a previously shaped toplift attached thereto and thereby making the smaller end of the heel-body smaller than the toplift, detaching the toplift, applying a cover to the trimmed heel-body, and re-attaching the original toplift 125 to the heel-body covered as aforesaid.

10. That improvement in methods of making 130 covered heels which consists in shaping

a heel-body according to a templet attached thereto in the place of the toplift and thereby reducing the lateral dimensions of the heel-body, adjacent to the templet, to less than those of the templet, detaching the templet, applying a cover to the trimmed heel-body, and attaching to the covered heel-

body a toplift of substantially the same lateral dimensions and contour as the templet.

In testimony whereof I have signed my name to this specification.

WILLIAM HUBBARD.
